UNITED STATES PATENT OFFICE.

ERNEST CADGENE, OF ENGLEWOOD CLIFFS, AND GEORGE DUPONT, OF PATERSON,
NEW JERSEY.

FABRIC-PRINTING MACHINE.

Application filed June 5, 1925. Serial No. 35,198.

This invention relates to improvements in methods and machines for printing fabrics, and is a continuation in part of our co-pending application, Serial No. 670,670, filed October 25, 1923.

The machine of the present invention is, generally speaking, of the type disclosed in our United States Patent No. 1,480,348, dated January 8, 1924.

- 10 In machines of the class shown in said patent, as heretofore constructed by others, it has been possible to produce only single colored ornamentations by one running of the fabric through the machine and while
- 15 multi-colored effects and designs employing the bas-relief stencil ornamentation as a part thereof have been heretofore produced, they have only been produced by hand labor and consequently have not been extensively used
- 20 because of the resultant high costs of production.

An object of the invention is to provide a new and improved construction of a machine capable of performing, in a single running of the fabric through the machine, a printing of a bas-relief ornamentation with one or more perforated stencils in connection with or supplementary to a printing of a flat ornamentation with one or more of the

- 30 usual solid printing rollers.

Another object is to so construct the machine that the line contacts against the pressure roller of the several printing devices employed may be adjusted so as to secure

- 35 an accurate registration of the component parts of the finished design.

A further object is to continuously maintain registration between the bas-relief and flat ornamentations by providing a positive

- 40 drive for the printing members employed which will cause said members to operate

in synchronism.

The above and other objects will appear more clearly from the following detailed

- 45 description, when taken in connection with the accompanying drawings, which illustrate a preferred embodiment of the inventive idea.

In the drawings—

- 50 Figure 1 is a side elevation of the machine constructed in accordance with the invention;

Figure 2 is a central longitudinal section through the machine;

- 55 Figure 3 is an end elevation;

Figure 4 is an enlarged fragmentary elevation illustrating the radial adjustment of the printing roller relative to the pressure roller; and

Figure 5 is a fragmentary diagrammatic illustration of a sample of the work printed in the machine.

Referring more particularly to the accompanying drawings, the numeral 10 indicates generally the frame of the machine at the front end of which is mounted the feed roller 11 carrying the fabric to be printed, said fabric being led from the roller beneath an idler roll 12 and from thence about a large pressure roller 13 against which the solid printing roller 14 and stencil 15 engage.

The pressure roller 13 is rotatably mounted in bearings 16 slidably in suitable guides in the frame 10 and vertically adjustable therein by means of screws 17. Any suitable driving means such as a pulley 18 and belt 19 leading to a convenient source of power may be employed for driving the roller 13.

The printing roller 14 is adjustable radially and circumferentially with respect to the pressure roller 13, the radial adjustment being provided for the purpose of varying the pressure of the printing roller against said pressure roller, while the circumferential adjustment is utilized for the purpose of effecting the registration between the flat ornamentation produced by the printing roller and the bas-relief or flock ornamentation implanted upon the fabric by the stencil 15. It will be understood that this registration is accomplished at the beginning of the operation of the machine, and mechanism, presently to be described, is employed for constantly maintaining this registration by the operation of the printing roller and stencil in synchronism with each other.

The radial adjustment of the printing roller 14 is accomplished by mounting the shaft 20 of the printing roller in bearings 21 slidably mounted in guides 22 in the frame 10 (Figure 4). Pressure screws 23 engage with adjacent faces of the bearings 21 to force the printing roller into printing contact with the fabric, compression springs 24 being provided for moving the roller 14 away from the pressure roller 13 when the screws 23 are released. In practice, sufficient pressure is applied to the printing roller by means of the screws 23 to cause

said roller to be positively driven by the pressure roller 13 when the latter is rotated.

The circumferential adjustment of the printing roller 14 with respect to the pressure roller 13 is effected by means of a worm 25 keyed to the shaft 20 of the printing roller and engaged by an adjusting worm 26 secured to the sprocket wheel 27 loosely mounted on the shaft 20. In order to make a circumferential adjustment of the roller 14 the screws 23 are first turned to relieve the pressure of the roller on the pressure roller 13 and the adjusting worm 26 is then turned. Inasmuch as the sprocket wheel 27, which carries the adjusting worm 26, is held from rotation by the gearing connected thereto (presently to be described) it will be apparent that rotation of the worm 26 will impart a similar movement of the roller 14 through the worm 25. After securing the desired amount of adjustment the screws may then be employed to force the printing roller against the pressure roller.

The rotation of the printing roller 14, when being driven by the roller 13, is employed to positively drive the stencil 15 in synchronism therewith so that the registration obtained by the circumferential adjustment of the roller 14 will be maintained throughout the operation of the machine. To accomplish the positive drive just mentioned the stencil 15 is provided upon each end thereof with a geared flange 28 and each flange meshes with a gear 29 rotatably supported by an arm 30 pivoted to the frame 10 at 31 and secured in position by an adjusting bolt 32 carried by the frame and engaged with said arm. The arm 30 also carries at each end thereof the sprockets 33 and 34 engaged by the chain 35 or similar driving element. Each chain 35 also engages an idler sprocket 36 pivotally supported by the frame 10 and further extends about another sprocket 37 mounted upon the countershaft 38 journaled in said frame. The shaft 38 carries a sprocket 39 engaged by a drive chain 40, or its equivalent, which also extends about the sprocket 27 and an idler sprocket 41, so as to transmit the rotary movement of the printing roller 14 to said shaft 38. Rotation of the latter is, in turn imparted to the gear 29 through the medium of the chain 35 to rotate the stencil 15 in the same direction as the printing roller and in synchronism therewith. It will be understood that the worms 25 and 26 form a coupling between the printing roller 14 and sprocket 27 which will cause said elements to rotate in unison when the printing roller is being driven by the pressure roller.

Printing composition is supplied to the roller 14 by any suitable means such as the inking roller 42 mounted in the bottom of the supply reservoir 43.

65 The construction of the stencil 15, the

mounting therefor, and the means for feeding the flock printing paste or composition therethrough, are similar, in some of its characteristics, to the construction shown in the above mentioned patent and hence a brief description will suffice for the purpose of the present machine. Said stencil is rotatably mounted for floating movement, insufficient to disengage the gears 28 and 29, on a non-rotatable support 44 in the form of a hollow drum having its ends secured in the sectional brackets 45 carried by the sides of the frame 10. A portion of the drum 44 is cut away as indicated at 46 to permit a combined pressure element and distributing blade 47 to contact with the inner surface of the stencil and hold it against the pressure roller 13. The pressure element 47 is provided with trunnions 48 removably mounted in the split bearings 49 formed in the brackets 50 adjustably secured to the brackets 45. To the projecting ends of the trunnions 48 are secured the lever arms 51 from which weights 52 are suspended for holding the element 47 with a yielding and constant pressure against the pressure roller 13.

A pipe 53, which is connected to a suitable reservoir (not shown) containing a supply of printing composition for the stencil 15, extends into the drum 44 and is provided with a plurality of nozzles 54 for delivering said composition to a trough 55 mounted within the drum and extending the length of said stencil. The bottom of the trough is perforated to permit the composition to flow onto a deflector plate 56 the lower edge of which terminates adjacent the lower edge of the element 47.

In practice, the fabric to be printed passes from the feed roll 11 beneath the idler roller 12 and from thence between the pressure roller 13 and the printing roller and stencil. The printing roller is provided with any suitable design, such as the leaves 57 (Figure 5), which is cut into the roller, or which may be formed in an electrotype detachably secured to said printing roller in accordance with the well known constructions of devices of this character. The stencil is provided with perforations which form, in effect, outlines for designs cut in the printing roller.

Before starting the machine, the printing roller is adjusted circumferentially, as previously described, to secure the proper relation between the same and the stencil so that the ornamentals produced by the respective members will be exactly registered with one another in order that the finished fabric will have the appearance shown in Figure 5. The machine is then started whereupon the fabric will first be printed by the roller 14 and thereafter have implanted thereon, by the stencil, the composition which produces the bas-relief orna-

mentation, which in the present instance is shown as a plurality of dots. As previously described, after the proper relative adjustment has been secured between the printing roller and stencil, this adjustment is maintained and the latter elements are positively driven in synchronism throughout the operation of the machine. After the printing by the stencil, the fabric is preferably led directly to a drying machine.

It will be understood that the diameters of the stencil and printing roller are exact multiples of one another to cause the repetition of the designs or ornamentations to be implanted upon the fabric in exact superimposed relation and also that if any of the printing members contain only a single unit of a motif for the final design in a circumferential direction, the contact line of such printing member with the pressure roller 13 would have to be located at such a distance from the contact line of the succeeding printing member as to cause the successive printings to be brought into proper registration.

While, for the purposes of illustration, only one printing roller is shown, it will be obvious that a plurality of such printing rollers could be employed in accordance with the number of colors which it is desired to reproduce in the finished product.

What is claimed is:

1. In the textile art, the method of printing a flock printing pattern in register with a color pattern, which comprises successively applying the color and flock printing patterns to the fabric while moving the fabric and said applying means synchronously and positively driving the flock applying means to maintain the respective patterns in register, the flock printing pattern being formed of flock printing material implanted on the fabric by means of a perforated stencil.
2. In the textile art, the method of printing a flock printing pattern in register with a color pattern, which comprises moving the fabric to be printed synchronously with a plurality of printing rollers and a flock printing stencil roller adapted to successively apply the color and flock printing patterns on the fabric, and positively driving said stencil roller in synchronism with said printing rollers to maintain the respective patterns in register, the flock printing pattern being formed of separated spots of material implanted on the fabric by forcing flock printing material through perforations in said stencil roller.
3. The combination in a fabric printing machine, of a pressure roller, a thin perforated stencil to produce a bas-relief ornamentation, said stencil being movable in juxtaposition to said pressure roller, a printing roller to produce a flat ornamentation,
- and means for driving said stencil in synchronism with said printing roller to maintain said bas-relief and flat ornamentations in register.
4. The combination in a fabric printing machine, of a pressure roller, a thin perforated stencil to produce a bas-relief ornamentation, said stencil being movable in juxtaposition to said pressure roller, a printing roller to produce a flat ornamentation, and gearing for positively driving said stencil in synchronism with said printing roller to maintain said bas-relief and flat ornamentations in register.
5. In a fabric printing machine, a pressure roller, a plurality of printing members arranged about said pressure roller in printing contact therewith, each of said printing members being movable in a single direction and being provided with suitable designs to print separate characteristics of a composite ornamentation, and one of said printing members comprising a thin perforated stencil in juxtaposition to said pressure roller to produce a bas-relief ornamentation, and gearing for positively driving said stencil in synchronism with the other printing member to maintain said bas-relief ornamentation in register with the ornamentation produced by said other printing member.
6. In a fabric printing machine, a pressure roller, a plurality of printing members arranged about said pressure roller in printing contact therewith, each of said printing members being movable in a single direction and being provided with suitable designs to print separate characteristics of a composite ornamentation, and one of said printing members comprising a thin perforated stencil in juxtaposition to said pressure roller to produce a bas-relief ornamentation, gearing for positively driving said stencil in synchronism with the other printing member to maintain said bas-relief ornamentation in register with the ornamentation produced by said other printing member, and means to permit said other printing member to be shifted independently of said stencil and relative to said pressure roller in a circumferential direction.
7. A machine for printing flat and bas-relief ornamentations on textile fabrics, including a pressure roller over which a single length of fabric is passed, a printing member cooperating with said pressure roller and movable in one direction only to print flat ornamentation on certain portions of said length of fabric as it is passed over said roller, and a stenciling member mounted above and capable of contact with said pressure roller and simultaneously operating relative to said printing member for producing bas-relief ornamentation on different portions of said length of fabric adjacent the

first named portions, which bas-relief ornamentation forms, in effect, an outline for said flat ornamentation.

8. A machine for printing flat and bas-relief ornamentations on textile fabrics, including a pressure roller, a printing member movable only in one direction and cooperating with said roller for producing flat ornamentation on one portion of fabric, a stencil 10 also cooperating with said pressure roller to print bas-relief ornamentation on a different portion of said fabric adjacent the first named portion, supporting means for said printing member, means for adjusting said 15 supporting means to vary the pressure of the printing member against said roller, and means to permit said stencil and printing member to be shifted independently of one another and relative to said pressure roller.
9. A machine for printing flat and bas-relief ornamentations on textile fabrics, including a pressure roller, a pair of printing members one of which includes a thin perforated stencil mounted adjacent said pressure roller and the other of which includes 25 a solid printing roller, bearings for said printing roller, resilient means acting against said bearings to normally force said printing roller away from said pressure 30 roller, means engageable with said bearings to force said printing roller toward said pressure roller against the pressure of said resilient means, and means to urge said stencil with a yielding pressure against said 35 pressure roller.

10. In the textile printing art, the method of printing a flock printing pattern in register with a color pattern, which comprises successively applying the color and flock 40 printing patterns to the fabric while moving the fabric and said applying means synchronously and maintaining the respective patterns in register, the flock printing pattern being formed of flock printing material implanted on the fabric by means of a 45 perforated stencil.

11. In the textile printing art, the method of printing a flock printing pattern in register with a color pattern, which comprises moving the fabric to be printed synchronously with a plurality of printing rolls, including color rolls and a flock printing 50 stencil roll adapted to successively apply the color and flock printing patterns on the fabric in proper register, the flock printing pattern being formed of separated spots of material implanted on the fabric by forcing flock printing material through perforations in said stencil roll.

12. In the textile art, the method of printing a flock printing pattern in register with a color pattern, which comprises successively applying the color and flock printing patterns to the fabric while moving the fabric 60 and said applying means simultaneously and

concomitantly, the flock printing pattern being formed of flock printing material implanted on the fabric by means of a perforated stencil roll.

13. In the textile art, the method of printing a flock printing pattern in register with a color pattern, which comprises moving the fabric to be printed simultaneously and concomitantly with a plurality of printing rolls, including color rolls and a flock printing 70 stencil roll adapted to successively apply the color and flock printing patterns on the fabric in substantial register, the flock printing pattern being formed of separate spots of material implanted on the fabric by forcing the flock printing material through the perforations in said stencil roll.

14. In a fabric printing machine, a pressure roller, a plurality of printing members arranged about said pressure roller in printing contact therewith, each of said printing members having operative movement in a single direction and being provided with suitable designs to print separate characteristics of a composite ornamentation, and one 85 of said printing members comprising a perforated stencil movable in juxtaposition to said pressure roller to produce a bas-relief ornamentation, and means whereby said printing members have substantially synchronous movement so that the separate characteristics of said composite ornamentation are in substantial register.

15. In a fabric printing machine, a pressure roller, a stencil cooperating with said roller for producing certain ornamentations, a printing member also cooperating with said roller for producing other ornamentations, said printing member having operative movement only in one direction, means whereby said printing member and stencil have substantially synchronous movement so that the ornamentations produced thereby are in substantial register, and means to permit said stencil and printing member to be shifted independently of one another and relative to said pressure roller.

16. The combination in a fabric printing machine, of a pressure roller, a perforated stencil to produce a bas-relief ornamentation positioned in juxtaposition to said pressure roller, a printing roll to produce a flat ornamentation positioned in juxtaposition to said pressure roller, and means whereby said printing member and stencil have substantially synchronous movement so that said bas-relief ornamentation is in substantial register with said flat ornamentation.

17. In a textile printing machine, the combination with an impression cylinder; of a color roll and a flock printing stencil roll arranged around said cylinder in cooperative printing relation thereto, means for rotating said cylinder and the respective printing rolls synchronously, and means for im-

planting the flock printing pattern on the register with the printed pattern from said fabric by forcing flock printing material through perforations in said stencil roll.

18. The textile machine as claimed in claim 17, in which means is provided for independently adjusting said flock printing roll to bring the printed pattern thereof in

color printing roll.

In testimony whereof we have affixed our signatures.

ERNEST CADGENE.
GEORGE DUPONT.
